ELEVATOR

Filed July 8, 1922

DV.

INVENTOR
A.O.W. Hansen
BY
F. Ledermann ATTORNEY

UNITED STATES PATENT OFFICE.

AUGUST O. W. HANSEN, OF NEW YORK, N. Y.

ELEVATOR.

Application filed July 8, 1922. Serial No. 573,604.

To all whom it may concern:

Be it known that I, AUGUST O. W. HANSEN, a citizen of the United States, residing at New York, in the county of New York and State of New York, have invented certain new and useful Improvements in Elevators, of which the following is a specification.

This invention relates to elevators and 10 has for its main object the provision of an elevator which is adapted to carry and lift a load of bulk from one level to another.

Another object is to provide an elevator 15 which has the complete lifting mechanism mounted beneath the platform so as to utilize a minimum amount of space. In this regard it is to be noted that the usual elevator has the lifting mechanism mounted in a pit adjacent to the elevator shaft consequently using more space than is required with this elevator.

These and other objects will become apparent in the description below, in which characters of reference refer to the like-named parts in the drawing.

Referring briefly to the drawing, Figure 1 is a top plan view of the elevator shaft with the doors in closed position.

Figure 2 is a front elevational view partly 30 in section of Figure 1.

Figure 3 is a side elevational view of Figure 2.

Figure 4 is a wiring diagram showing the 35 circuits leading to the reversible motor.

Describing the drawing in detail, the numeral 1 indicates a substantially square lift platform which has a semi-circular arch 2 secured to its top side.

The upper portion of the elevator well 4 40 is framed by the side channels 3 from which anchor hooks 5 project.

Pulleys 6 rotatably secured to the said channels 3 cradle cables 7. One end of each of said cables 7 is secured to the platform 1 and have a rectangular counter weight 8 secured to the free ends thereof.

Bearing brackets 9 secured to the under-side of the platform 1 rotatably journal a horizontal shaft 10 upon which a relatively 50 large worm gear 11 is fixed. The ends of said shaft 10 is provided with grooved winding drums 12. A conventional type of reversible electric motor 13 is also secured to the underside of the platform 1, and the extending portion of the motor shaft 14 is

formed into a worm 15 which meshes with the aforesaid worm gear 11.

A pair of lift cables 16 are secured to the hooks 5 and pass downwardly and around the platform pulleys 17, the latter being secured in brackets 18. The ends of said lift cables 16 are secured to the grooved winding drums 12 so that in rotating the latter, the cable will be paid out or taken up from the lower peripheral surface to hooks at 60 the rear end of the shaft 4 and pass around the rear platform pulley 20, the latter being secured in brackets 21. The lower end of said cables 19 are secured to the winding drums 12 and take up or pay out from the 65 upper peripheral surface of the said grooved drums.

A switch handle 22 is mounted on the circular arch 2 and is connected in electrical series to the motor 13 by the leads 25 and 70 23. The circuit is normally open and rotation of the switch handle closes the said circuit. An electrical battery 24 connected in series to the lead 24 energizes the motor 13 when the circuit is closed. A reversible 75 type of switch may be installed in the circuit to reverse the rotation of the motor. A diagrammatic view of the reversing switch is shown in Figure 4, in which the field coil of the motor is indicated by the 80 numeral 29 and is connected in parallel with the armature of the motor thru a pole changer or reversing switch 30.

The elevator well 4 is provided with the 85 usual type of doors 27 which are secured to the side walls of the shaft hinges 28.

In operation the elevator platform is lifted from the bottom of the shaft 4 by manipulation of the switch handle 22, by 90 which the circuit will be closed. By operating the reversing switch 30 in conjunction with the switch 22, the platform will be lifted or lowered as desired, by the motor mechanism. As the worm 15 meshes with the worm gear 11, the grooved drums 12, at the outer ends of the gear shaft 10, will rotate and take up the cables 16 and 19 thereby lifting the platform 1 to the upper level. In rising to the upper level, the arch 2 contacts with the underside of the doors 27 and rotates the latter to the open position. As the elevator is lowered and as the doors 27 at all times lean toward the arch frame 2, said doors will automatically 100 close when the platform is descending. 105 110

I claim:

An elevator comprising a vertical movable platform, a well receptive of said platform, brackets on the corners of said platform, pulleys mounted on said brackets, additional brackets between each pair of pulleys, a shaft rotatable in the last-named brackets, grooved drums on said shaft aligned with the pulleys, cables secured to the upper portions and at each corner of the well, the lower ends of said cables being trained about said pulleys, said pulleys being adapted to divert the course of said cables to the horizontal position, each drum

having one pair of cables secured thereto, 15 one cable on each drum entering the same tangential to its upper periphery, the opposite cable being secured tangentially on the lower periphery of the same drum, the cables on each drum being adapted to be 20 wound on the same in opposite directions, a gear on said drum shaft, a motor secured to the movable platform, and a worm shaft 25 engaging the gear for rotating said drum shaft.

In witness whereof, I affix my signature.

AUGUST O. W. HANSEN.
